RELAY

William D. Macgeorge, Woodbury, N. J., assignor
to Automatic Temperature Control Company,
Inc., Philadelphia, Pa., a corporation of Penn-
sylvania

Application October 8, 1935, Serial No. 44,014

10 Claims. (Cl. 175—320)

This invention relates to relays, and particularly to differential relays for alternating current circuits.

Relays as developed in the past arranged to respond to small alternating currents have been possessed of disadvantages in that the return to neutral position has been sought by the use of springs or gravity or the like, with most unstable results.

10 It is among the objects of this invention; to improve relay constructions generally; to provide a relay for small current conditions with a predetermined neutral setting which is obtained without the exercise of any but electrical forces; to provide a differential relay with a coil in series with a source of alternating current to move an armature to a neutral position when another coil in series with the first is deenergized; to provide a relay which is statically and 15 electrically balanced; to provide a relay arranged to respond to a small alternating current to control a circuit and arranged to respond to a second alternating current circuit in phase with the first to actuate the relay to vertical or centered position; and many other objects and advantages will become more apparent as the description proceeds.

In the accompanying drawing forming part of this description;

30 Fig. 1 represents a diagrammatic plan of a relay constructed in accordance with the preferred form thereof;

Fig. 2 represents a similar diagrammatic plan of the preferred form of relay in a circuit with 35 a Wheatstone bridge circuit and arranged to actuate the relay in accordance with the unbalance- ing of the bridge.

While the preferred form of relay will be shown as possessed of two opposed deviating or 40 diverting coils in addition to the neutralizing coil, it will be understood that but one need be used, or that two may be used in series.

As the relay has many points of use, it will first be described as the unit to be incorporated 45 in any desired circuits, and quite independent of a given circuit, in contrast to the combination shown in Fig. 2.

Referring to Fig. 1, any suitable support, as 50 the panel 10 may be provided, having a pivot point 11, upon which the lever 12 is pivoted, and preferably having on one side of the pivot 11 the contact element 13, disposed between the opposed contacts 14 and 15, having connectors respectively 16 and 17, each forming one contact 55 of independent circuits, the other contact of

each of which is the common lead 18, connected to contact 13 through the lever 12 in such manner as to impose no strain, torque, or other resistance to movement, of the lever 12. In this connection it will be clear that connector or lead 5 18 might be electrically connected through the pivot 11 if desired. It will be understood, of course, that connectors 16 and 18 are in one circuit, say for instance (and purely illustratively) in a circuit with one field of a reversible motor (not shown), while connectors 17 and 18 are in another circuit, say the opposite field of such reversible motor.

The lever 12 has operatively associated with it an armature or solenoid core or bar 20 carried 15 by the preferably insulated and at least non-magnetic bracket 21, usually, but obviously not necessarily, on the opposite side of said pivot 11 from the contacts 13, 14 and 15. A centering and polarizing coil 22 is disposed about the armature bar or core 20 having its ends connected to terminals 23 and 24, for attachment to a suitable source of electrical energy. Preferably the source is alternating current although direct current can obviously be used to effect the 20 same centering function as later recited, and the coil and armature arrangement is such that generation of alternating current magnetic flux in the centering coil 22 moves the solenoid core to centered relation, if the latter is free to move, 30 and also maintains the armature in centered relation in the coil, with a consequent maintenance of the contact 13 in equally spaced relation 35 relative to contact 14 and contact 15. Obviously during existence of this positioned condition 35 of the lever and contacts, neither circuit 16 and 18 or 17 and 18 is closed. Obviously energization of coil 22 by alternating current instantaneously polarizes the ends 40 and 41 of armature 20, with polarity which reverses with the alterations of current.

Suitably supported on the panel or the like 40, preferably in axial alignment with the solenoid core or armature 20, is a deviating or energizing coil 25, having at one end a terminal 45 or connector 26, and at the other end a similar connector 27, which may be directly coupled to a suitable source of current to be described, or may lead to another auxiliary or amplifying diverting or energizing coil 28, at the opposite end of 50 the armature or core 20, which is wound oppositely from coil 25, and terminates in connectors or terminals 30 and 39. Coil 28 obviously might have separate connectors and be in a separate circuit from coil 25, and this is contemplated, as 55

shown in Fig. 1. It is to be understood that it is not necessary always to provide two coils, as a single coil can perform adequately in certain connections, but two coils in the same circuit 5 amplify the push-pull effect on the armature. It is preferred that coil 25 (and coil 28 if provided) be connected with a suitable current source or independent sources of variable strength, preferably alternating current, varying 10 from no potential to a plus or minus of small or great strength or amplitude according to demands.

Referring to Fig. 2, the same relay structure as just described relative to Fig. 1, will be observed, as will the diagrammatic showing of a Wheatstone bridge circuit, as the illustrative source of the fluctuations in the operating coil of the relay. Assume one lead 19, of a power line of alternating current comprised of lines 29 15 and 19, in which line connectors 23 and 24 of the neutralizing or centering coil 22, are placed so that a continuous flow of alternating current through coil 22 is insured, and, which is of great importance also, so that the circuit through 20 coil 22 is exactly in phase with the alternating current selectively energizing the coil 25 (and/or 28), as will be described. Lead wire 19 leads to one end of the bridge circuit comprised of arms 33 and 34 on one side, having the tap-off lead 30 35, and arms 36 and 37 on the other side, and having the tap-off lead 38.

In the preferred form of invention, as shown in Fig. 2, the tap-off leads 35 and 38, are respectively joined with connectors 26 and 30, (with 35 the opposite leads 27 and 39 joined) and the elements or legs 33 and 34, and 36 and 37 of the bridge are in balance so that the alternating current impressed by leads 19 and 29 is balanced on each side of the bridge. It will be clear that 40 at that time alternating current will be flowing in coil 22 so that the alternating current magnetic flux is effective to center the core 20 and thus to maintain the contact 13 out of engagement with either contact 14 or 15 of the secondary 45 circuits, as there will be no current whatever impressed between bridge tap-off leads 35 and 38, and therefore coils 25 and 28 will not be energized.

It may be assumed that the Wheatstone bridge 50 circuit is one in which the resistance in one leg is varied in accordance with variations in condition, which condition is susceptible to change in accordance with controlling motion of the reversible motor illustratively mentioned as having 55 fields in the secondary circuits controlled by contacts 13, 14 and 15. Illustratively the condition might be temperature and the balanced condition of the bridge might be a desired temperature condition, while temperature fluctuations 60 either way would have corresponding resistance variations and would therefore cause the impressing of a positive or negative current condition between tap-off leads 35 and 38 which would therefore impress a positive or negative current 65 flow between leads or connectors 26 and 30 through deviating coils 25 and 28.

While the same alternating current flow maintains through the neutralizing or centering coil 22, in which the ends 40 and 41, of core 20, would 70 be alternately polarized in accordance with the phase of the alternating current feeding the coil, it may be assumed that instantaneously, for purposes of description only, core end 40 will be "N" while core end 41, is, of course, "S".

In the preferred form of device, the bridge circuit is in phase with the alternating current passing through the coil 22, so that the polarization of coils 25 and 28 will be in phase with that of coil 22.

Assume a temperature deviation such as to cause a positive flow of alternating current through coils 25 and 28 so that instantaneously coil 25 has the end 42, adjacent the core end 40, of "N" polarity, with, of course, the other end 10 43 of "S" polarity. It will be evident that as the end of core 20, at 40 is instantaneously "N", as is the adjacent end 42 of coil 25, there will be mutual repulsion so that core 20 is pushed away from coil 25 about pivot 11, and relay or secondary circuit contact 13 engages fixed contact 14 to complete a secondary circuit. This action can be had, of course, from coil 25 alone.

Obviously, with coils 25 and 28 in series, but reversed, the instantaneous value or polarity of end 44 of coil 28 adjacent end 41 of core 20 with its instantaneous "S" polarity, will be "N", so as to attract core 20 toward itself, and thus to amplify the urge of the relay out of its centered position about pivot 11, as will be obvious. As 25 the instant polarity of core 20 shifts due to alternations of the current in coil 22, the instant polarity of the respective ends of coils 25 and 28 will shift in phase so that the resultant urge on core 20 is the same. Owing to the balance 30 of the relay there will be no disturbing vibration, torque, or urge effective on the relay at the time of alternation of polarity of core ends 40 and 41, as the coils 25 and 28 are in phase therewith. The centering and actuating or deviating 35 currents must be in phase when alternating current is used to secure a good firm non-chattering contact. This is important.

Assuming that the closing of circuit 13-14 as just described has effected a change of condition 40 through running such motor (not shown), and that responsive thereto the unbalance of the bridge is corrected and balance thereof is restored, then the current flowing through coils 25 and 28 will stop, and the continuing energization 45 of coil 22 will be effective on solenoid core 20 to center same and moving about pivot 11 to move contact 13 away from fixed contact 14 and to break the secondary circuit therethrough, but without permitting contact 13 to touch opposite 50 contact 15 of the other secondary circuit.

Obviously a change of resistance of the bridge legs so as to cause a negative flow through coils 25 and 28, would instantaneously find end 42 of coil 25 of "S" polarity when the instantaneous 55 polarity of end 40 of core 20 was "N", so that core 20 would be attracted toward coil 25, to swing contact 13 against contact 15, to close the secondary circuit thus controlled by those contacts. Obviously also, the instantaneous value of end 44 of coil 28 would be "S" so as to repulse the "S" pole of end 41 of the core.

While many uses will occur to those skilled in the art, other than as disclosed, as for instance 65 in any desired situation where coil 25 (and 28 if provided) may be subjected to direct current, while the centering coil 22 is subjected either to alternating current or direct current, certain uses may be pointed out, as follows:

Situations in which the relay will be available 70 in other circuits in mechanical and electrical assemblies will doubtless occur to those skilled in the art, but mention must be made of a selected few of such uses that have occurred to 75

me in the connection and which may be listed as follows:

a. Alternating current or direct current Wheatstone bridge circuits in accordance with the instant disclosure.

b. Photoelectric bridge in comparison of colors or light intensities in which the deviating coils may be energized positively or negatively in accordance with the departure from a given value 10 of photoelectric devices (not shown) in their circuits.

c. Approximate time delay relay. In this situation a variable constantan rheostat controls the circuit through one deviating coil while a fixed 15 nickel resistor arranged to operate at a high temperature (not shown) controls a flow through the other deviating coil. If the resistances are initially the same when the current is turned on the relay will be balanced until the nickel resistor 20 heats up sufficiently so as to increase the strength of current flowing through the second mentioned deviating coil to close one circuit of the relay. By adjusting the variable constantan rheostat the length of time required to close the relay 25 can be varied.

d. Under voltage under current relay. In this application a current proportionate to the line voltage passes to one deviating coil while a current proportionate to the line current passes to 30 the other or secondary deviating coil. If an excess of current passes through the line the attraction of the secondary deviating coil will exceed that of the primary deviating coil and the relay will act. Conversely if the voltage in 35 the line falls below normal the relay will also act.

e. Reverse current relay. A current transformer (not shown) is in series with a primary deviating coil, while the secondary deviating coil and the centering or neutralizing coil are both 40 excited from a potential transformer having constant voltage characteristics.

f. Speed synchronizer. Two detached direct current magnetos (not shown) are respectively coupled in driven relation to the equipment to be synchronized, and produce voltages proportional to the speed of their drivers, and which respective voltages are impressed upon the respective opposite deviating coils of the relay. When the speeds are identical the relay will hold and be 50 held in its neutral position. Any variation in relative speed of the respective equipments will actuate the relay and actuate indicator or control equipment.

g. Polarized alternating current or direct current relay. In this use the centering coil is energized from a source having characteristics similar to the actuating source and the relay will operate in accordance with the polarity of the 55 actuating source.

The absence of mechanical agencies to actuate or return the relay parts to neutral will be appreciated, as will the fact that the relay thus provided is susceptible to extremely minute or 60 weak currents to exert its proper relay function.

I claim:

1. A differential relay comprising a deviating coil having an axis, an armature core, means mounting the armature core for guided movement, the core disposed adjacent to said coil substantially concentric with the axis thereof, a polarizing and centering coil relative to which the core has movement and disposed so that the core is in its field, and the core and centering 70 coil acting together as a solenoid, circuit con-

trolling means operatively associated with the armature core.

2. A differential relay comprising a support, a deviating coil mounted fixedly on the support, an armature core, means mounting the armature core for guided movement relative to the support, the core disposed in such proximity to said coil as to be within the magnetic field thereof, a centering coil fixed relative to the support in such proximity to the core as to be within the 10 magnetic field thereof and relative to which the core has guided movement, the centering coil and core acting together as a solenoid, circuit controlling means operatively associated with the core.

3. A differential relay comprising a support, a lever, means pivotally mounting the lever on the support in static balance, an armature core mounted on the lever for movement therewith, a centering coil mounted fixedly on the support 20 in position to loosely embrace the core and to exert a solenoid centering action thereon, a deviating coil fixedly mounted on the support adjacent to the core with its axis substantially concentric with the core and with the core within the magnetic field of the deviating coil, circuit controlling means operatively associated with the lever.

4. A differential relay comprising a support, a lever, means pivotally mounting the lever on the support, an armature core mounted on the lever, a centering coil fixed on the support and loosely embracing the core and forming with the core a solenoid to center the core and hold the lever in a predetermined angular position relative to 30 the pivotal mounting, a deviating coil mounted on the support adjacent to one end of the core in substantially concentric relation to the core so as to urge the core out of its centered position in the centering coil when suitably energized, a second deviating coil fixedly mounted on the support adjacent to the other end of the core in substantially concentric relation to the core so as to urge the core out of its centered position in the centering coil when suitably energized, electrical connecting means joining the deviating coils in series but in reversed relation 40 so that each augments the urge of the other on the core.

5. In a relay, an armature having a neutral 50 position and a circuit closing position, circuit controlling means operatively associated with the armature, means supporting the armature for guided movement between neutral and circuit closing position, a hollow fixed polarizing and 55 centering coil adjacent to said armature, a core mounted on the armature and disposed within the coil and in neutral position, a deviating coil fixed relative to the centering coil adjacent to said core whereby its magnetic flux is effective on said core to move the armature to circuit making position.

6. In combination, a source of A. C., a fixed polarizing and centering coil continuously in circuit with said source, a fixed deviating coil in 65 circuit with said source, an armature including a core, said core disposed within and forming with the centering coil a solenoid, said core being disposed within the magnetic field of said deviating coil, means mounting the core for guided movement between its solenoid position and a modification thereof incident to energization of the deviating coil, means for energizing the deviating coil with A. C. current of selected polarity 70 instantaneously identical with or exactly oppo-

site to that flowing in the centering coil so that their zero points occur at the same instant, and circuit controlling means controlled by said armature.

- 5 7. In combination with a source of alternating current, a relay comprising an armature core, means mounting the core for limited guided movement, a centering coil loosely embracing and fixed relative to said core and forming with
10 said core a solenoid, a deviating coil fixed relative and adjacent to said core and centering coil and having an axis substantially concentric to said core, means including connections between said source and said centering coil and deviating
15 coil whereby the centering coil is continuously energized with said alternating current and the deviating coil is arranged for energization with alternating current of selected potential in exact phase with that of the centering coil although
20 selectively of the same or opposite direction whereby the deviating coil exerts attraction or repulsion on said core, and circuit controlling means operated by said armature core.

8. A differential relay comprising a support, a
25 lever arm, means mounting the lever arm for pivoted movement relative to said support, a core, a centering coil fixed to the support and loosely embracing said core, a yoke having spaced legs engaging the core on opposite sides of said centering coil and mounted on said lever arm to permit limited substantially axial movement of the core in the centering coil by movement of said lever about its pivot, and a deviating coil mounted on
30 the support adjacent to and substantially concentric with the core beyond the yoke.
35

9. A differential relay comprising a support, a lever arm, means mounting the lever arm for pivoted movement relative to said support, a core, a centering coil fixed to the support and loosely embracing said core, a yoke having spaced legs 5 engaging the core on opposite sides of said centering coil and mounted on said lever arm to permit limited substantially axial movement of the core in the centering coil by movement of said lever about its pivot, a pair of deviating coils 10 spaced apart and fixed to the support and each substantially concentric with and adjacent to the core on opposite sides of the yoke.

10. A differential relay comprising a support, a lever arm, means mounting the lever arm for 15 pivoted movement relative to said support, a core, a centering coil fixed to the support and loosely embracing said core, a yoke having spaced legs engaging the core on opposite sides of said centering coil and mounted on said lever arm to permit limited substantially axial movement of the core in the centering coil by movement of said lever about its pivot, a pair of deviating coils 20 spaced apart and fixed to the support and each substantially concentric with and adjacent to the 25 core on opposite sides of the yoke, and connections joining the deviating coils in series in reversed directions so that with a current flowing through both coils the instantaneous polarity of the end of one coil adjacent to one end of the 30 core is opposite to that of the end of the other coil adjacent to the other end of the core so that the deviating coils supplement each other.

WILLIAM D. MACGEORGE. 35
